CHASER ASSEMBLY

Frederic Nell, Waynesboro, Pa., assignor to Landis Machine Company, Waynesboro, Pa., a corporation of Pennsylvania

Application May 22, 1940, Serial No. 336,666

19 Claims. (Cl. 10—103)

This invention relates to circular chaser assemblies such as are employed on taps and die heads. It is more particularly concerned with means for initially adjusting such chasers to their correct cutting position for any particular diameter, or for resetting them to the same diameter after they have been ground for re-sharpening purposes.

In my prior patent, No. 2,120,621, granted June 14, 1938, I disclosed an invention which marked a decided forward step in the design and usefulness of circular chaser assemblies, as it embodied means for rigidly securing the chasers to the holders and yet afforded means for adjusting the chasers by small amounts without removing them from the holders, through the use of an adjustable finger. In some classes of service, however, my prior assembly is open to certain disadvantages. The chief defect of my prior assembly is the tendency to break the finger member thereof through causes other than the excessive stresses under which it was expressly designed to be broken. I have found that it is impossible to obtain or heat treat a metal so that the finger is sufficiently tough as to withstand considerable but unexcessive surge stresses, and yet has a sufficiently hard surface to resist the abrasion occasioned by the cooperating screws. Repeated adjustments sometimes result in wearing away or "necking down" the central portion of the finger, so that it snaps under loads which it was originally designed to resist.

My present circular chaser assembly does not employ a safety device which is quite so sensitive; however, it does provide a reasonable degree of safety against breakage of the chasers or holder parts, and in addition is so designed that wear will not unduly weaken my adjustment member. Further, my entire assembly now is more adapted to economical machining because fewer parts are employed, and they do not involve any special or exacting consideration, due to their particular shape.

The very simplicity of my present structure has inherent advantages from the operating standpoint because the device is self-locking, requiring the operator to expend but a very minimum of time to secure the desired adjustment. Further, the chaser may be reground without removing it from the holder, and a major adjustment then made to reposition it in the proper cutting position in but a fraction of the time formerly employed.

Accordingly, it is the primary object of my invention to provide a novel chaser assembly which

is very simple in construction, very precise in adjustment, very rugged under all operating conditions, and yet which incorporates reasonable safety measures to avoid the breakage of more costly parts thereof.

It is a further important object of my invention to provide a circular chaser assembly having adjustment means which require a minimum expenditure of the operator's time and effort to effect both minor cutting adjustments and major adjustments, such as are necessary after repeated regroundings of the chaser.

Another object is to provide a circular chaser assembly having means for effecting coarse or major adjustment of the chaser in equal increments, and a fine adjustment for securing a final or rake angle adjustment of the chaser.

It is a further object to provide a chaser assembly having a single, rotatable self-locking member for effecting minor adjustment of each chaser.

Another object of my invention is to provide a novel circular chaser assembly which is equally adapted for use in taps or die heads.

A further object is to generally improve and refine certain details of the chaser assembly shown in my prior patent.

Further objects of my invention will be apparent from the following description thereof when taken in conjunction with the accompanying drawing and from the appended claims.

In the drawing,

Figure 1 is a longitudinal sectional view of one of my novel circular chaser assemblies;

Figure 2 is a view looking from the left hand side of Figure 1, with the chaser removed and with certain parts broken away and in section to more clearly illustrate the construction;

Figure 3 is an enlarged cross-sectional view showing part of my adjustment mechanism disposed in one extreme adjusted position;

Figure 4 is a view similar to Figure 3, but shows my adjustment mechanism disposed in the opposite extreme adjusted position;

Figure 5 is a front view of the assembly; and

Figure 6 is a fragmental, enlarged sectional view showing the cooperating serrations of the bushing members.

Referring to Figures 1, 2 and 5, circular chaser 10 is mounted upon a holder 11. The latter is provided with a camming element 13 for coaction with the camming member of a die head or tap to move the said holder 11 radially inward or outward, and also has a guide 9 adapting it for sliding movement on a die head or tap. These features are shown more fully in my prior patent,

No. 2,100,449, granted November 30, 1937, and as they form no part of the present invention, they will not be further described.

A clamping screw 14 is utilized to fasten chaser 10 to holder 11, the latter having a threaded bore for receiving said screw. It should be noted that screw 14 maintains the under surface 29 of chaser 10 in firm engagement with the upper surface 21 of holder 11, thereby assuring that the thread-cutting serrations 25 of chaser 10 are properly located with respect to surface 21.

Holder 11 is accurately counterbored to receive a lower or adjusting bushing member 30 and the flange of an upper bushing member 31, which rests thereupon. Bushings 30 and 31 are adapted to be locked against relative rotation by serrations 32 on member 30 and serrations 33 on member 31. Upper bushing 31 is provided also with a pilot surface 35 which coacts with a cylindrical surface 40 in chaser 10 to very accurately center the chaser and to prevent any radial play thereof. Thus, chaser surfaces 20 and 40 and the flange of bushing 31, very accurately determine the relationship between the thread-cutting serrations 25 and the work.

Chaser 10 has a splined bore 50 which coacts with splines 51 on bushing 31 to lock the chaser to the bushing. Thus, any angular adjustment of lower bushing or adjustment bushing 30, through interfitting serrations 32 and 33 results in an exactly equal angular adjustment of bushing 31, and since the latter is coupled to the chaser by splines 51, this results in effecting a similar angular adjustment of the chaser.

To effect such adjustment, holder 11 has a bore 60 in which is located an adjustment pin 65 having at one end a reduced, slightly eccentric extension 66, which fits into a recess 67 in adjustment bushing 30. The other end of adjustment pin 65 rests against a counterbored face 69 in bore 60 and is provided with a suitable socket 70 for an adjusting wrench. The wrench may be applied to socket 70 from the rear of the holder after the latter has been removed from the die head or tap.

When it is desired to rotate chaser 10 to effect a minor angular adjustment thereof, such as is necessary to establish the correct relation between the thread-cutting serrations 25 and the work, adjustment pin 65 is rotated the proper amount to cause eccentric end 66 to effect the proper degree of rotation of adjustment bushings 30 and 31, and chaser 10. The amount of adjustment which can be secured by rotating pin 65 from one extreme position to another (through 180 degrees) is but slightly greater than the pitch of the serrations 32 and 33 (see Figures 3 and 4); consequently, very accurate adjustments can be effected. Further, the slight amount of eccentricity of end 66 of pin 65 is sufficient to render the arrangement self-locking. In other words, no matter how great the forces developed in the chaser during the thread-cutting operation, bushing 30 cannot effect rotation of the eccentric 66, no matter what angular position it may assume. Even when the center of eccentric portion 66 is disposed directly above or below the axis of the body 65, the assembly nevertheless is self-locking. This is readily understood when it is realized that the degree of offset of the two axes is so small, that any turning moments applied to portion 66 result in the development of high frictional forces at the point of engagement of the adjustment bushing with portion 66, and also between bore 60 and body 75

65, which accordingly produces a resistance moment of greater magnitude than the turning moments applied. In other words, the greater the turning moment applied, the greater will be the resulting frictional resistance moment. Consequently, it is apparent that adjustments can be made with a minimum of time and effort, for a slight rotation of pin 65 is all that is required, and that the adjusting pin is self-locking.

10 When it is required to resharpen the thread-cutting serrations 25, the operator need only loosen clamping screw 14 a sufficient amount to permit the adjustment serrations 31 and 33 to disengage. The fit between the chaser bore 40 and pilot surface 35 is so close that when the chaser is lifted the adjustment bushing 31 is carried therewith. The chaser and adjustment bushing then are rotated the pitch of one or more adjustment serrations and the adjustment serrations 32 and 33 again are permitted to engage. It is apparent that the smallest adjustment possible is the pitch between any two adjacent serrations.

Thus, the chaser 10 can be sharpened without 25 removing it from holder 11, and a minimum of loosening of the parts is involved. In former assemblies it was necessary to loosen the screw 14 sufficiently to permit the splines 50 and 51 to be disengaged; consequently, there was little saving of time and effort as compared to removing the chaser entirely from the holder. The relatively shallow depth of serrations 32 and 33 eliminates this disadvantage, while the multiplicity employed assures economical tool life because 30 the chaser can be adjusted by very small angular increments. Moreover, since pin 65 may be used to angularly adjust the chasers from an infinitely small angle to an angle greater than that corresponding to the pitch of one adjustment serration, it is not necessary to grind the chasers, with respect to the serrations or any fractional part thereof; however, when a considerable amount of the chaser needs to be ground away to sharpen it, my present arrangement makes it possible to do so with a minimum 35 of time and effort. Pin 65 also provides an extremely precise rake angle adjustment of the chasers.

Although I have shown bushing member 31 as 40 being separate from, and splined to, chaser 10, and preferably use this combination of elements, because it makes it possible to more accurately and inexpensively machine chaser surface 20, it is to be understood that the invention is just 45 as advantageous in assemblies in which bushing 31 and chaser 10 are combined as a single integral element, and the appended claims are intended to embrace the invention where it is so employed.

The safety feature of the present invention resides in giving eccentric 66 an effective cross-sectional area which is somewhat less than either (1) the effective shearing area of serrations 32 and 33, or (2) the effective shearing area of splines 51. Therefore, should the machine be subjected to destructive forces, eccentric 66 will shear off, thereby protecting the more costly parts of the machine. I have found that by using a shearable pin, the apparatus will maintain an accurate setting between chaser grindings, and substantially no wear occurs which would weaken the adjustment mechanism.

A further important feature of the apparatus resides in the novel manner in which the adjusting pin is associated with the structure. By

providing shoulder 69 in bore 60, and a blind recess 67 in bushing 30, pin 65 is securely restrained against accidental endwise displacement from the holder, and yet it may be readily removed when desired by removing the chaser and bushings from the holder.

Referring to Figures 1 and 6, serrations 32 and 33 are preferably provided with slant and straight sides and are so disposed that when cutting forces developed in the chasers result in a tendency to move bushing 31 in the direction indicated in Figure 6 by the arrow, the turning moment is taken by the straight or axially directed portions of the serrations. This precludes the development of axially directed forces which might tend to lift face 20 of the chaser off of the holder.

It is also to be understood that the novel chaser assembly of the invention is equally useful in dies as well as taps, the only change necessary being to rotate the chasers through approximately 180°, to dispose their cutting edges inwardly rather than outwardly, and moving them outwardly the required distance to cut a thread on the external rather than the internal surface of the work, to thereby adapt them for threading an external, rather than an internal surface, and the appended claims are intended to cover the chaser assembly irrespective of whether it is used in a tap or die.

From the foregoing it is apparent that the present invention constitutes an efficient thread-cutting mechanism of extremely simple construction, having relatively few parts; it is very precise in adjustment, the adjustment being infinitely variable by small increments; it is very rugged, all the moving parts having considerable bearing areas; it provides a reasonable safety feature in the form of a shearable adjusting pin, which is not subjected to localized wear; and it is so designed that a bare minimum of time and effort is required to effect either minor or major chaser adjustments.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed and desired to be secured by United States Letters Patent is:

1. In a thread-cutting device, a chaser holder; a circular chaser assembly mounted on said holder for limited rocking movement about a fixed axis; and means for rocking said chaser about said axis, comprising a self-locking rotatable device, having an eccentric portion, mounted in said holder and operably connected to said chaser assembly.

2. In a thread-cutting device, a holder; a circular chaser assembly mounted on said holder for limited rocking movement about a fixed axis; and means for rocking said chaser assembly about said axis, comprising a pin mounted for rotation about an axis spaced from and parallel to said fixed axis and having an eccentric head seating in a recess in said chaser assembly.

3. In a thread-cutting device, a holder having a pair of parallel openings therein; a chaser assembly; a screw threaded into one of said open-

ings and mounting said chaser assembly for rocking movement on said holder; an adjusting pin mounted for rotation in said other opening and having an eccentric end engaging a recess in said chaser assembly; and a shoulder on said holder cooperating with the other end of said pin for limiting axial movement of said pin away from said chaser assembly.

4. A circular chaser assembly comprising a chaser holder; a circular chaser mounted on said holder; a chaser bushing; means for non-rotatably coupling said chaser bushing to said chaser; an adjustment bushing adjustably secured to said chaser bushing; and means for effecting rotation of said adjustment bushing with respect to said holder.

5. A circular chaser assembly comprising a chaser holder; a circular chaser mounted on said holder; a bushing coupled to said chaser; an adjustment bushing coupled to said first bushing; and means for effecting rotation of said adjustment bushing, comprising a rotatable pin mounted in said holder and having an eccentric and coacting with a recess in said adjustment bushing.

6. A circular chaser assembly comprising: a chaser holder; a circular chaser mounted on said holder; a bushing located between said chaser and said holder and having splines coacting with similar splines located in said chaser; an adjustment bushing having adjustment serrations coacting with adjustment serrations located on said first-named bushing; and means for effecting rotation of said adjustment bushing into any one of a plurality of angular adjusted positions.

7. A circular chaser assembly comprising: a chaser holder; a circular chaser mounted on said holder; a bushing having splines coacting with similar splines located in said chaser and having a pilot coacting with a bore in said chaser; an adjustment bushing having adjustment serrations coacting with adjustment serrations located on said first-named bushing; and means for effecting rotation of said adjustment bushing, comprising a rotatable pin coacting with said adjustment bushing and capable of rotating the same an angular distance greater than the pitch of said adjustment serrations.

8. A circular chaser assembly comprising: a chaser holder; a circular chaser mounted on said holder; a bushing having splines coacting with similar splines located in said chaser and having a pilot coacting with a bore in said chaser; an adjustment bushing having adjustment serrations coacting with adjustment serrations located on said first-named bushing; and means for effecting rotation of said adjustment bushing; said means comprising a rotatable pin having a reduced, eccentric end coacting with a recess in said adjustment bushing, the eccentricity of said reduced end being greater than the pitch of the said adjustment serrations.

9. A circular chaser assembly comprising: a chaser holder; a circular chaser assembly mounted on said holder and having adjustment serrations coacting with adjustment serrations located on an adjustment bushing; and means for effecting rotation of said adjustment bushing, comprising a self-locking, rotatable pin located in said holder and having an eccentric end coacting with a recess in said adjustment bushing, the eccentricity of said reduced end being greater than the pitch of said adjustment serrations, but insufficient to effect undesirable

counter-rotation of said pin in response to cutting forces developed in said chaser.

10. In combination, a chaser holder; a circular chaser; means supporting said chaser for rotational adjustment on said chaser holder; means for effecting major angular adjustment of said chaser; and means for effecting minor angular adjustment of said chaser; said latter means comprising an eccentric pin mounted for rotation in said chaser holder, and coacting with said means for effecting major angular adjustment of said chaser.

11. In combination, a chaser holder; a circular chaser; means supporting said chaser for rotational adjustment on said chaser holder; means for effecting major angular adjustment of said chaser; and means for effecting minor angular adjustment of said chaser; said latter means comprising a pin having an eccentric end cooperating with a recess in said means for supporting said chaser, and whose eccentricity is at least equal to the smallest adjustment which can be effected by said means for effecting major adjustment of said chaser.

12. A chaser holder, a chaser on said holder; means for effecting major rotational adjustment of said chaser by fixed increments; means for effecting minor rotational adjustment of said chaser; said latter means comprising a self-locking eccentric mechanism operably associated with said chaser holder and having sufficient eccentricity to effect rotational chaser adjustment at least equal to the increments of adjustment effected by said major adjustment means, but having insufficient eccentricity to permit counter-rotation of said eccentric mechanism through rotative stresses imposed on said chaser.

13. In combination, a chaser holder having a circular chaser mounted thereon; means for supporting said chaser in desired relation with respect to said holder, comprising a member secured to said holder and connected to said chaser by splined surfaces, said member further having adjustment serrations located thereon; and means for effecting rotational adjustment of said chaser, comprising a pin with a reduced, eccentric end, said reduced end having less shearing area than the shearing area of said splined surfaces and of said adjustment serrations.

14. A circular chaser assembly comprising: a chaser holder having a circular chaser mounted thereon; a chaser bushing disposed between said holder and said chaser and splined to said chaser; an adjustment bushing disposed between said holder and said chaser bushing and having adjustment serrations coacting with similar serrations located on said chaser bushing; and means for effecting rotational adjustment of said adjust-

ment bushing, the height of said adjustment serrations being considerably smaller than that of said splines, whereby said serrations may be disconnected to adjust said chaser without disconnecting said chaser from said chaser bushing.

15. In a chaser assembly, a holder; a chaser device mounted for limited rotation on said holder and having a plurality of serrations projecting toward said holder; a member disposed between said chaser device and said holder and having serrations interfitting with said first-named serrations; and an eccentric pin cooperating with a recess in said member for adjusting said chaser angularly with respect to said holder, said pin having less effective shearing cross-sectional area than said serrations.

16. In a thread cutting device, a chaser holder, a circular chaser assembly mounted on said holder for limited rocking movement about a fixed axis, and having a pair of spaced walls, offset from said axis; and means for rocking said chaser about said axis, comprising a member having opposed curved surfaces having a common center of curvature and coacting with said walls, said member being mounted for rotation on said holder about an axis substantially parallel to said fixed axis and located between said opposed curved surfaces, but being offset from the common center of curvature thereof.

17. The thread cutting device defined in claim 16, wherein said walls are formed in a disc-like element, and said member is located substantially wholly within the periphery of said disc-like element.

18. In a thread cutting device, a support; a circular chaser assembly mounted on said support for rocking movement about a fixed axis; and means for rocking said chaser assembly about said axis, comprising a member rotatable about an axis spaced from and disposed substantially parallel to said fixed axis and having an eccentric portion seating in a recess provided in a part operably connected to said chaser assembly and operable to rock said chaser assembly when said member is rotated about its axis.

19. In a thread cutting device, a chaser holder; a circular chaser assembly mounted on said holder for limited rocking movement about a fixed axis; and means for rocking said chaser about said axis, comprising a self-locking rotatable device, having an eccentric portion, mounted in said holder and operably connected to said chaser assembly, the eccentric portion of said device being adapted to be sheared by excessive stresses acting upon said chaser before any detrimental distortion thereof occurs.

FREDERIC NELL.
